UNITED STATES PATENT OFFICE

2,670,465

INITIATOR MANUFACTURING APPARATUS

Charles Russell Johnson, Glen Mills, Pa., assignor to E. I. du Pont de Nemours and Company, Wilmington, Del., a corporation of Delaware

Application May 21, 1952, Serial No. 289,023

3 Claims. (Cl. 340—265)

1
The present invention relates to a machine for use in the manufacture of blasting initiators. More particularly, this invention relates to a probing device adapted to check the initiator shells for proper loading of the explosive charges.

Blasting initiators generally are manufactured by loading a sensitive explosive charge capable of detonating a blasting explosive into a metal shell, and providing an ignition charge in association with this charge, the ignition charge being adapted to become ignited by the action of a fuse or a heated bridge wire and to initiate the main or base charge. In the case of electric initiators, the installation of the bridge wire assembly is a final step in the manufacture of the initiator, while in the case of a fuse-ignitable initiator, the pressing of the last charge completes the fabrication operation. In many types of initiators, more than two charges of explosive material are used, and, in some cases, the final charge consists of a loose powder into which a bridge wire is inserted. In practically all cases, the main charge and the charge adapted to ignite the main charge are compacted by a pressing operation during the assembly of the initiator.

Since blasting initiators of various types are mass produced by means of automatic fabricating and loading machines, it is essential that accurate and efficient means be provided to insure against defective initiators. Due to the nature of the explosive compositions used in initiators, it is desirable to reduce the handling of the uncompleted initiators by personnel to a minimum, not only from a safety viewpoint, but also to eliminate human error.

One major cause of defective blasting initiators has been uneven loading of the pressed charges. By far the greater number of initiators produced annually are loaded by automatic loading devices, and, while these devices are efficient and accurate in controlling the quantity of explosive inserted into a shell, it sometimes happens that an insufficient quantity of explosive material is present in the loading machine, or that one or more of the loading ports becomes closed or inoperative, thereby producing an initiator without any charge or an inadequate charge.

It is an object of the present invention to provide a completely automatic initiator charge checking device. A further object of the present invention is to provide a device for rapidly and accurately inspecting partially assembled initiator charges. Additional objects will become apparent as the invention is more fully described.

I have found that the foregoing objects may be

2
attained when I provide an initiator probing device having a plurality of individual probes adapted to be entered into a block of initiator shells, said probes being held in an extended position normally, but being capable of being depressed upon encountering resistance to further motion into the initiator shells, a means for detecting whether all of the probes have been depressed a sufficient amount, and a means for indicating the presence of any defectively loaded shells.

To more fully describe my invention, reference is made to the accompanying drawings which illustrate a specific embodiment, it being understood that the invention is not limited thereto. In the drawings:

Figure 1 represents a partially sectional frontal view;

Figure 2 represents a partially sectional side view;

Figures 3, 4 and 5 represent a detail view of the probe action and detecting means;

Figure 6 represents a detail view of the indicator operation; and

Figure 7 shows a suitable signal and control circuit.

Referring to the figures in greater detail, 1 represents the structural support for the apparatus, 2 represents a shaft connecting the probing assembly with motive means (not shown) for lowering and raising the assembly, 3 is the housing of the probing assembly mounted on base plate 4 and suspended on shaft 2. Within the housing 3 are the probing elements 5 and the detecting plate 6. The probing elements 5 contain an enlarged portion and are positioned by means of bores 7 in the housing 3, and guide bushings 8 in base plate 4, and held normally extended by coil springs 9. Directly beneath each probing element 5 is an initiator shell 10 supported and positioned by conventional means (not shown).

Between the shells 10 and the base plate 4 is the shell locking plate 11 suspended on bolts 12. Each bolt 12 has a projecting arm 13 secured to the upper end, and passes through a support member 14 mounted on base plate 4. The plate 11 is maintained in an extended position by coil springs 15. Each of the plates contains openings for the passage of the probing elements.

Detecting plate 6 projects beyond both the front and rear of housing 3, and is movable therein, the forward end being contacted by spring blade 16, and the rear edge carrying roller 17 which travels on plate-return disc 18. The plate-return disc 18 is mounted on shaft 19 which in

turn is connected to a mechanical means (not shown) for applying and removing pressure to roller 17. Mounted on housing 3 above the detector plate 6 is microswitch 24 aligned with pin 23 on plate 6.

Mounted on support 1 on each side under arm 13 are the shell-locking plate 11 and stops 20. These stops are positioned below arm 13 a distance equal to the normal distance between the tops of the shells and the bottom of the shell-locking plate 11, and are adjustable so that the device may be used with different length shells.

In Figures 3, 4 and 5, the initiator shells are represented as containing base charge 21 and a priming charge 22. The probe 5 is designed as to contact only the priming charge 22 or in its absence, to enter the depression in charge 21 it would otherwise occupy. It will be understood that the depression in the base charge 21 would be produced by the first pressing operation.

In operation, the procedure is as follows:

A block of initiator shells 10 from the loading machine is positioned under the probing assembly, either by mechanical or manual means, and the housing 3 lowered by lowering shaft 2. Plate 11 descends with housing 3 until the arms 13 contact the stops 20. At this time, plate 11 is just touching the tops of the shells, thus insuring that all shells are properly seated and upright. The continued downward movement of shaft 2 causes the probing elements 5 to enter the shells, and compresses springs 15, bolts 12 being prevented from further downward movement.

During the downward movement of housing 3, mechanical pressure is exerted on plate 6 through shaft 19 and disc 18, holding the plate forward so that probing elements 5 are not bound. When the probing elements 5 contact the charge 22, the resistance to further downward movement is sufficient to depress them into bores 7 against the weak pressure of springs 9.

When the downward motion of shaft 2 reaches a predetermined point, disc 18 is automatically retracted, and further downward motion of housing 3 prevented. If the enlarged portions of probing elements 5 are all depressed above plate 6, the pressure from spring blade 16 is sufficient to move the plate 6 rearward so that pin 23 actuates the microswitch 24. If one or more of the pins are not depressed sufficiently so that the enlarged portion of element 5 is not above plate 6, rearward motion of plate 6 is prevented, and microswitch 24 will not be actuated.

In the embodiment shown, microswitch 24 closes a by-pass circuit which actuates the motive means required to raise shaft 2. As housing 3 rises, spring tensions of springs 15 holds the shell-locking plate 11 on the shells, thus permitting withdrawal of the probing elements 5 without danger of a shell rising with the element 5. Continued upward movement of shaft 2 restores the assembly to its original position. As soon as a new cycle is begun, the pressure from shaft 19 and disc 18 will return detector plate 6 to its normal position, and elements 5 will again be in the extended position. In the event the assembly is not automatically raised, i. e., if the microswitch 24 is not actuated, the operator will be signaled by conventional means, such as a bell or light, and will then use a separate by-pass circuit to raise the assembly, and recover the rejected block of shells.

A convenient conventional type control and signal circuit is set forth in Figure 7. Referring to the figure, operation of the device is com-

menced by manually depressing start switch 26. Power is supplied from power source to the stop and start circuit through contact *b* of the start switch. Relay 28 is thereby actuated and remains actuated through its normally open contact *a*. Contact *b* of relay 28, on closing, actuates relay 30 through one of either bottom limit switch 25, switch 24 or reset switch 31. Normally open contacts *b* and *c* of relay 30, upon actuation complete the power supply circuit to the motor 32. The opening of normally closed contact *a* of relay 30, breaks the circuit to the warning device 33. Contact *a* of the start switch actuates relay 34 and power is thereby supplied through its single normally open contact to solenoid 35, shifting reverse clutch 36 to its position for raising. The action of the mechanism continues the raising until top limit switch 31 is momentarily opened. Opening of top limit switch 31 closes switch 38 which is ganged to it. In this manner, relay 39 is energized and its single normally open contact is closed. Power is then supplied to solenoid 40, the reverse clutch being thereby shifted to the down position, opening of switch 37 having deactivated relay 34 and solenoid 35. The downward motion can be interrupted by opening of normally closed bottom limit switch 25, thereby cutting off power to relay 30. Power is cut off through its contacts *b* and *c* and supplied to the warning device through its contact *a*. In normal operation, however, when all initiator shells are properly loaded, switch 24 is closed momentarily as bottom limit switch 25 opens. Switches 41 and 42 are ganged to switch 24. The closing of switch 24 causes switch 41 to open and switch 42 to close. Power is thereby cut from solenoid 40 and supplied to solenoid 35. This reverses the mechanism into its raising cycle. Thus, the reciprocating action of shaft 2 will continue indefinitely unless both switches, 24 and 25, are simultaneously opened. When this occurs the motor is stopped and the warning device is actuated. The operator can raise the device and remove the defective shells by simultaneously depressing start switch 26 and reset switch 31. The operation can also be stopped through stop switch 29.

It will be apparent that this checking device can readily be utilized in either a completely automatic initiator shell assembly set-up, or as an individually operated inspection station. The full operating cycle requires only a very short period of time, and only simple adjustments are required to adapt the device for use with shells of different sizes or of charges of different depths.

The embodiment illustrated is considered "fail-safe," in that continued operation of the assembly is interrupted if the probing elements are not properly depressed, and thus a block containing a defective shell cannot be accidentally overlooked. It would obviously be feasible to have the microswitch control a circuit to a light or a bell to signal the operator, or to automatically remove a block containing a defective shell.

Many variations of the controls devices required to make the operation automatic are possible, and they form no part of the present invention. Thus, conventional microswitch arrangements may be set up to actuate the various motive means to produce the desired sequence of operation. Also, the selection of the motive means for actuation of the shafts 2 and 19 is not a part of the present invention. Since explosive compositions are present, it may be preferable to use pneumatic or hydraulic units to re-

duce the hazard of sparking. The materials usable in the construction of the various parts of the assembly is limited only to those non-reactive to the explosive composition, since there are no moving parts apt to produce sparks in the vicinity of the shells.

In view of the many variations which may be made in the design and operation of the present invention, I intend to be limited only by the following claims.

I claim:

1. A charge checking device for initiator shells comprising a housing having a plurality of vertical bores, an initiator shell positioning area below said housing, a horizontally movable plate within said housing having openings normally in axial alignment with said bores, probing elements projecting below said housing passing through said plate openings and guided by said bores, said probing elements being normally maintained in a downwardly extended position, and having an area of substantially the same diameter as the plate openings at that portion normally at the plate level, and an area of reduced diameter immediately below said portion, means for lower-

25

ing said housing a predetermined distance towards said shell positioning area, whereby said probes enter initiator shells and contact a charge therein, means exerting a horizontal force on one end of said movable plate, signal means responsive to horizontal motion of said plate, means for raising said housing to the original level, and means for returning said plate to said normal position.

10 2. A device as claimed in claim 1, wherein the signal means comprises a by-pass circuit actuated by a microswitch.

15 3. A device as claimed in claim 1, wherein the probing elements are normally maintained in an extended position by compression springs.

CHARLES RUSSELL JOHNSON.
